UNITED STATES PATENT OFFICE

CARL ALFRED LARSSON, OF WESTMINSTER, LONDON, ENGLAND, ASSIGNOR TO VICKERS-
ARMSTRONGS LIMITED, OF LONDON, ENGLAND, A BRITISH COMPANY

MOUNTING FOR AUTOMATIC GUNS

Application filed February 15, 1929, Serial No. 340,046, and in Great Britain March 22, 1928.

This invention relates to mountings for automatic guns and has for its chief object to provide improved means whereby the mounting can be converted from one in which the gun fires at the usual low angles of elevation (herein termed ground firing) into one in which the gun can be fired at high angles of elevation (herein termed anti-aircraft firing).
 According to the invention the cradle or elevating arm on which the gun is mounted is constructed at its rear to receive a trunnion pin passing through the usual trunnion lug on the mechanism casing so that by adjusting the said cradle or elevating arm upon the crosshead of the mounting until it approaches the vertical, and retaining it in this position, the mounting is converted from the ground firing condition into the anti-aircraft firing condition in which the gun can be conveniently sighted and fired by the gunner when sitting on the ground with his legs between the rear legs of the mounting in the case of a tripod mounting or in the case of a cone or pedestal mounting with his legs at each side of the mounting.

The cradle preferably comprises two side members rigidly connected together at a suitable distance apart and provided between them with an elevating gear which, when the mounting is to be converted from the ground firing condition into the anti-aircraft firing condition, is disconnected from the mechanism casing of the gun and swung about its pivots into a housed position between the said side members where it is held by means of spring clips.

The ammunition box may be carried by a bracket adjustably mounted on the cradle so that when the mounting is converted into the anti-aircraft condition the said box can be caused to occupy a position such that the cartridge belt passes as straight as possible up to the feed box of the gun. For this purpose the said bracket may be rotatably mounted on a spigot projecting laterally from the cradle and this bracket may be held in the required position suitable for ground firing or for anti-aircraft firing by a spring plunger carried by the bracket and

adapted to engage in one or other of two holes provided in part of the cradle.

In order that the said invention may be clearly understood and readily carried into effect, the same will be more fully described with reference to the accompanying drawings, in which:

Figure 1 is a side elevation showing a tripod gun mounting according to this invention in the ground firing condition, 69

Figure 2 is a view similar to Figure 1 showing the gun mounting in the anti-aircraft firing condition,

Figure 3 is a side elevation on a larger scale of part of the cradle (with one side member removed) showing how the elevating gear is held in the housed position when not in use, 65

Figure 4 is an end view showing the spring clips of Figure 3, and 70

Figure 5 is a plan on a larger scale of the ammunition box bracket and its associated parts.

A is the gun, B is the cradle or elevating arm to which the gun is trunnioned by means of a detachable trunnion pin A¹ passing through a hole b (Figure 2) in the cradle and through the usual trunnion lug on the front part of the mechanism casing of the gun, and C is the usual crosshead in which the said cradle is trunnioned at B¹ and which is mounted for training movements in a support D carried by the tripod legs D¹. 75

In the construction shown the cradle B comprises two side members rigidly connected together with distance pieces between them and is held in any desired angular position for ground firing by means of a clamp C¹ which is carried by the crosshead C and cooperates with arc-shaped parts B² of the side members of the cradle. The usual screw elevating gear E is pivoted at E¹ between the side members of the cradle and is connected by a detachable connecting pin E² to the usual elevating lug A² on the mechanism casing. 90 The side members of the cradle are extended rearwardly and slightly downwardly and the rear ends of the extensions are formed with coinciding holes B³ for the reception of the aforesaid trunnion pin A¹ when the mount- 95

ing is to be adjusted for anti-aircraft firing. To effect this adjustment the gun is detached from the cradle by removing the trunnion pin A¹ and the aforesaid connecting pin E² and is remounted on the rear end of the cradle by passing this trunnion pin through the aforesaid holes B³ in the rear end of the side members of the cradle and through the hole in the trunnion lug of the mechanism casing. The clamp C¹ for the cradle is then released and the cradle is raised from the rear about the trunnions B¹ connecting it to the cross-head C until the cradle is nearly vertical as shown in Figure 2. The cradle may be held positively in this position by means of a pin C² (Figure 2) passing through a hole C³ (Figure 1) in the front part of the crosshead C and through holes B⁴ (Figure 1) in the front parts of the side members of the cradle; the latter may also be held by tightening the aforesaid clamp C¹. The gun can then be elevated freely about the trunnion pin A¹ at the end of the cradle, the gunner occupying a sitting posture on the ground between the rear legs of the tripod. The elevating gear E, which is not required for use in this condition of the mounting, is swung about its pivot E¹ into a housed position between the side members of the cradle where it is retained by spring clips E⁵, E⁶ (Figures 3 and 4) carried by the said side members. The said spring clips engage resiliently with the boss of the elevating handwheel when the elevating gear is swung into the housed position as shown by dotted lines in Figures 3 and 4.

F is the aforesaid bracket having recessed end walls F^x, F^y (see Figure 5) which slidably receive the ammunition box F¹ shown by dotted lines in Figures 1 and 2. This bracket is rotatably mounted on a spigot F² projecting laterally from one of the side members of the cradle B and is held in the required position suitable for ground firing or for anti-aircraft firing, by a spring plunger F³ carried by the said bracket and adapted to engage in one or other of two holes b¹, b² formed in a plate b² on the said side member. For ground firing the bracket F occupies a position such that the open end of the ammunition box F¹ is immediately beneath the feed box of the mechanism casing as is customary and as is shown in Figure 1, whilst for anti-aircraft firing the said bracket occupies the position shown in Figure 2 such that the ammunition box lies lengthwise of the cradle B with the open end uppermost, the ammunition belt thus being in a favourable position for entering the feed box.

Although the improvements have been shown in association with a tripod gun mounting they can equally well be employed with a cone or pedestal gun mounting in which case, when the mounting is in the anti-aircraft firing condition, the gunner sits on

the ground or deck with his legs at each side of the mounting.

What I claim and desire to secure by Letters Patent of the United States is:—

1. An automatic gun mounting comprising in combination a cradle or elevating arm on which the gun is mounted, said cradle or elevating arm having two side members rigidly connected together at a suitable distance apart and being provided at its rear with means to receive a trunnion pin passing through the usual trunnion lug on the mechanism casing of the gun so that by adjusting the said cradle or elevating arm upon the crosshead of the mounting until it approaches the vertical and retaining it in this position the mounting is converted from the ground firing condition into the anti-aircraft firing condition, a pivoted elevating gear disposed between said side members this elevating gear when the mounting is to be converted from the ground firing condition into the anti-aircraft firing condition being disconnected from the mechanism casing of the gun and swung about its pivots into a housed position between said side members, and means for holding said elevating gear in the housed position.

2. An automatic gun mounting comprising in combination a cradle or elevating arm on which the gun is mounted, said cradle or elevating arm having two side members rigidly connected together at a suitable distance apart and being provided at its rear with means to receive a trunnion pin passing through the usual trunnion lug on the mechanism casing of the gun so that by adjusting the said cradle or elevating arm upon the crosshead of the mounting until it approaches the vertical and retaining it in this position the mounting is converted from the ground firing condition into the anti-aircraft firing condition, a pivoted elevating gear disposed between said side members this elevating gear when the mounting is to be converted from the ground firing condition into the anti-aircraft firing condition being disconnected from the mechanism casing of the gun and swung about its pivots into a housed position between said side members, and spring clips for holding said elevating gear in the housed position.

3. An automatic gun mounting comprising a cradle or elevating arm on which the gun is mounted, means at the rear of said cradle or elevating arm to receive a trunnion pin passing through the usual trunnion lug on the mechanism casing of the gun so that by adjusting the said cradle or elevating arm upon the crosshead of the mounting until it approaches the vertical and retaining it in this position the mounting is converted from the ground firing condition into the anti-aircraft firing condition, and an ammunition box bracket adjustably mounted on the

cradle or elevating arm so that when the mounting is converted into the anti-aircraft condition said ammunition box can be caused to occupy a position such that the cartridge belt passes as straight as possible up to the feed box of the gun.

4. In an automatic gun mounting, the combination with the elements claimed in claim 1, of an ammunition box bracket adjustably mounted on the cradle or elevating arm so that when the mounting is converted into the anti-aircraft condition said ammunition box can be caused to occupy a position such that the cartridge belt passes as straight as possible up to the feed box of the gun.

5. In an automatic gun mounting, the combination with the elements claimed in claim 2, of an ammunition box bracket adjustably mounted on the cradle or elevating arm so that when the mounting is converted into the anti-aircraft condition said ammunition box can be caused to occupy a position such that the cartridge belt passes as straight as possible up to the feed box of the gun.

6. An automatic gun mounting comprising a cradle or elevating arm on which the gun is mounted, means at the rear of said cradle or elevating arm to receive a trunnion pin passing through the usual trunnion lug on the mechanism casing of the gun so that by adjusting the said cradle or elevating arm upon the crosshead of the mounting until it approaches the vertical and retaining it in this position the mounting is converted from the ground firing position into the anti-aircraft firing condition, an ammunition box bracket adjustably mounted on the cradle or elevating arm so that when the mounting is converted into the anti-aircraft condition said ammunition box can be caused to occupy a position such that the cartridge belt passes as straight as possible up to the feed box of the gun, a spigot projecting laterally from said cradle or elevating arm upon which spigot said bracket is rotatably mounted and a spring plunger carried by said bracket and adapted to engage in one or other of two holes in part of the cradle or elevating arm so as to hold said bracket in the required position suitable for ground firing or for anti-aircraft firing.

7. In an automatic gun mounting, the combination with the elements claimed in claim 1, of an ammunition box bracket, a spigot projecting laterally from the cradle or elevating arm upon which spigot said bracket is rotatably mounted, and a spring plunger carried by said bracket and adapted to engage in one or other of two holes in part of the cradle or elevating arm so as to hold said bracket in the required position suitable for ground firing or for anti-aircraft firing.

8. In an automatic gun mounting, the com-

bination with the elements claimed in claim 2, of an ammunition box bracket, a spigot projecting laterally from said cradle or elevating arm upon which spigot said bracket is rotatably mounted, and a spring plunger carried by said bracket and adapted to engage in one or other of two holes in part of the cradle or elevating arm so as to hold said bracket in the required position suitable for ground firing or for anti-aircraft firing.
